US00D969131S

(12) **United States Design Patent** (10) **Patent No.:** **US D969,131 S**
Lu (45) **Date of Patent:** **** Nov. 8, 2022**

(54) **MONITOR**

(71) Applicant: **Shenzhen G-world Technology Incorporated Company**, Shenzhen (CN)

(72) Inventor: **Yi Lu**, Shenzhen (CN)

(**) Term: **15 Years**

(21) Appl. No.: **29/776,830**

(22) Filed: **Apr. 1, 2021**

(51) LOC (13) Cl. **14-02**

(52) U.S. Cl.

USPC **D14/375**

(58) **Field of Classification Search**

USPC D14/125-127, 140.2, 149, 203.1, D14/203.7-203.8, 209.1, 221, 224.1, 227, D14/238.1, 300, 302, 305-307, 314, 336, D14/371, 373-377, 448, 496, 499-451, D14/900-902; D20/39, 41-42

CPC G06Q 20/18; G09F 13/00

(57) **CLAIM**

The ornamental design for a monitor, as shown and described.

DESCRIPTION

FIG. 1 is a front perspective view of a monitor showing my new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings depict portions of the monitor that form no part of the claimed design.

1 Claim, 6 Drawing Sheets
